UNITED STATES PATENT OFFICE.

JOHN HENRY DEWHURST, OF ATTERCLIFFE, SHEFFIELD, ENGLAND.

METHOD OF AND APPLIANCE FOR STRIPPING INGOTS FROM INGOT-MOLDS.

1,323,255.

Specification of Letters Patent.

Patented Dec. 2, 1919.

Application filed October 1, 1918. Serial No. 256,397.

To all whom it may concern:

Be it known that I, JOHN HENRY DEWHURST, subject of the King of Great Britain and Ireland, residing at Dewhursts Engineering Company Limited, Attercliffe, Sheffield, England, have invented new and useful Improved Methods of and Appliances for Stripping Ingots from Ingot-Molds, of which the following is a specification.

10 My invention relates to the stripping of ingots from ingot molds of the type in which a portion of the mold bottom is removable and capable of being pushed upward by pressure externally applied in order to remove the ingot from the mold. My invention consists in an improved method of and appliances for effecting that operation characterized by the employment of molds with loose fitting bottoms or plugs as above 15 described, but connected with such bottoms are stalks formed plain or with ratchet teeth to engage with a hinged pawl in proximity thereto, the said plugs co-operating with hydraulic rams to remove the ingots from the 20 molds, suitable permanent abutments being provided to prevent the molds rising and in case cars are employed, to prevent the cars also from rising. My invention though applicable to the stripping of ingots cast in 25 molds fixed in casting pits of Siemens furnaces of Bessemer converters, is more especially adapted for use in cases where ingots are cast in molds mounted on cars or bogies. In connection with my invention I employ 30 molds of the kind in which the ingot is cast large end uppermost.

My invention will be better understood on reference to the accompanying two sheets of drawings in which:

40 Figure 1 is a side elevation of a casting car (in section) and overhead stops employed in stripping ingots.

Fig. 2 is a plan view and Fig. 3 is an end view of same.

45 Fig. 4 is an end elevation of a casting car and side framing of stripping apparatus with swing stops.

Fig. 5 is a similar view of a car in a casting pit with fixed stops on the side framing.

50 The same letters refer to similar parts throughout the several views.

I will first describe my invention as applied to casting cars. To the top of such a car I fit a strong hematite iron plate *a*, to 55 form the ingot mold bottom plate, and at

the same time to overhang the sides of the framing of the car and protect the wheels and draw bar gear from any overflow of molten metal, said plate *a*, also being provided with means for holding the ingot 60 molds in position, a convenient arrangement being the formation of undercut slots *a*¹ Fig. 4 on the plate *a* to engage with flanges *b*¹ on the lower ends of the molds *b*. Any desired number of molds may be placed on 65 a car, but I find either two or four to be the most suitable.

The bottom and smaller end of each ingot mold is either solid or closed in except for a central hole *b*², coinciding with a similar 70 hole in the bottom plate *a*, through both of which holes passes a downwardly depending stripping plug *c*. The stalk of this plug, which may either be integral with or separate from the plug proper is provided with 75 a ratchet tooth or teeth engaging with which is a pivoted pawl *d*.

Shortly after the ingots have been cast in the molds, the car is run on a rail track to a stripping machine, in connection with 80 which a pit is formed below the rail-road in which are situated a series of hydraulic rams *e*, *e*. Each car is in turn passed over the pit and makes contact with a stop, in which position the before described plugs *c*, 85 are directly over the hydraulic rams *e*, *e*, so that when the latter are put into operation the plugs *c*, force the ingots upward in the molds for any desired distance according to 90 the size of the ingot, but sufficiently to afford a good hold for the gripping tongs of an overhead crane which either then or subsequently takes hold of the ingot and removes it entirely from the mold. If the gripping 95 tongs do not deal with the ingots directly, the car is moved away from the hydraulic rams, but the ingots are still maintained in their raised position by reason of the pawl *d*, which is always held up against the stalk of the plug *c*, engaging with one of the teeth formed thereon.

After the ingots have been removed from the molds *b*, the stripping plugs *c*, are again lowered by means of an attendant turning the shafts on which the retaining pawls *d*, are fitted so that the latter become disengaged from the teeth on the stalks of the plugs *c*, which can then descend into their normal position.

In order to prevent the car being lifted off the track by the upward pressure of the 110

rams, in the case of an ingot sticking in the molds and requiring extra pressure to remove it, I provide stops *f*, on the sides of the stripping pit or other structure, arranged to overhang the deck of the car on each side and at a little distance above it. These stops *f*, may be permanent fixtures (as shown in Fig. 5) or pivotally mounted (as in Fig. 4) so that they automatically hang or swing into position over the car, but as it may be necessary to withdraw them to permit of the passage of a locomotive along the track, means are provided whereby this may be effected by an attendant.

15 As an alternative to the last described means for preventing the lifting of the car when the rams engage "sticker" ingots, I provide an arrangement of overhead stops, such for instance as beams or joists *g*, with 20 open ended longitudinal slots between same (see Figs. 1, 2 and 3), fixed at a little distance above the top of the molds, *b*, longitudinal slots between the beams being formed of a size to admit of the passage of 25 the ingots through them but at the same time to engage with the sides of the molds, *b*, and afford an abutment to prevent them rising. The adoption of this last described means permits of the free passage of a locomotive along the track at all times, as the overhead stops would be quite clear of same.

30 It will be obvious that the application of my invention to the stripping of ingots in casting pits, will be on very similar lines to that above described. If desired the ratchet and pawl mechanism in connection with the 35 plugs may be dispensed with, as the hydraulic pressure in the cylinders can be maintained until the ingots have been lifted clear of the molds.

40 From the foregoing description it will be seen that by my invention a considerable saving in time is effected by reason of the ingot molds not having to be handled so frequently as is the case in ordinary stripping operations, in fact when once an ingot mold has been fixed in position either on a car or in a pit, it need not be removed until it is worn out, thus saving the time and labor 45 which would ordinarily be involved in handling such mold both before and after every cast in addition to which by reason of the ingots being dealt with more expeditiously, they are very much hotter than usual when 50 placed in the soaking pits, which tends to a saving in fuel.

Having now described my invention what I claim as new and desire to secure by Letters Patent is:—

60 1. A mechanism for stripping ingots from molds, comprising plugs seated in the bottom of said molds and adapted to have vertical movement therein, which plugs have stems provided with ratchet teeth, and means

for engaging said teeth thereby to hold the 65 plugs in raised position.

2. In a mechanism for stripping ingots from molds, the combination with a casting car, of an overhanging plate, molds adapted to be held in position by said plate, said 70 plate and mold having registering openings, and means adapted to close the openings in the molds and provided with stems passing through the openings in said plate.

3. In a mechanism for stripping ingots 75 from molds, the combination with a casting car of a superimposed overhanging plate, molds adapted to be held in position on said plate, means carried by said plate and mold for stripping ingots from the molds, and 80 pivoted swinging stops for preventing the lifting of the car during the stripping operation.

4. In a mechanism for stripping ingots 85 from molds, the combination with a casting car of a superimposed overhanging plate, molds adapted to be held in position on said plate, said molds and plate having registering openings therein, movable plugs adapted to close the openings in said molds, and 90 having stems passing through the openings in the plate, such stems being provided with ratchet teeth, means for engaging said ratchet teeth for holding the plugs in raised position, and means for preventing the lifting of the car during the stripping operation. 95

5. In a mechanism for stripping ingots from molds, the combination with a casting car, of molds provided with openings in 100 the bottom thereof, a plug adapted to close each of said openings, said plug being provided with a stem having ratchet teeth, means for engaging said ratchet teeth thereby to hold the plug in raised position, and 105 means for engaging the molds to prevent the lifting thereof during the stripping operation.

6. In a mechanism for stripping ingots 110 from molds, the combination of a plate having a plurality of openings therein, a mold adapted to be held on said plate over each of said openings, said mold having an opening in the bottom adapted to register with the opening in the plate, a flange formed on the 115 bottom of said mold, lugs formed on said plate and having an undercut portion adapted to engage the flange of the mold, thereby to retain the same with its opening in register with the opening in the plate, a 120 plug adapted to close the opening in said mold and having a stem projecting through the opening in the plate, and means for engaging said stem, thereby to hold the plug in raised position.

In testimony whereof I have signed my name to this specification.

JOHN HENRY DEWHURST.
